MOTOR OPERATED ADJUSTING
MECHANISM

Edwin X. Schmidt, Milwaukee, Wis., assignor to
Cutler-Hammer, Inc., Milwaukee, Wis., a corporation of Delaware

Application August 4, 1940, Serial No. 351,313

13 Claims. (Cl. 48—180)

This invention relates to improvements in motor operated adjusting mechanisms.

A primary object of the invention is to provide a novel means for insuring a temporarily accelerated rate of adjustment of an indicating and/or controlling device in one direction or the other upon each required change of adjustment thereof from one direction to the other, to thereby provide for more rapid and more accurate operation of such device.

Another object is to provide means for substantially reducing or minimizing the time period of the hunting cycle of the adjusting mechanism incident to each initial change in the direction of adjustment resulting from each opposite change in the value of a condition to be controlled.

Another object is to provide a motor operated adjusting mechanism of the aforementioned character whereby a control mechanism involving a minimum amount of operating force may be employed.

Another object is to provide an adjusting mechanism of the aforementioned character which is adapted to compensate to a large degree for the inherent time lag in response of the control mechanism to changes in value of the condition to be controlled.

Another object is to provide an adjusting mechanism of the aforementioned character whereby the value of a condition to be controlled is maintained substantially constant.

Another object is to provide a gas mixing control system wherein said adjusting mechanism may be employed.

Another object is to provide a gas mixing control system including two of said adjusting mechanisms, one of which is utilized to effect proper proportioning of the combustible gases, and the other of which is adapted to effect proper indication of the potential heating value of the gaseous mixture.

Another object is to provide a control system wherein said adjusting mechanism is utilized to provide for maintenance of a substantially constant temperature in a heating oven or the like.

Another object is to provide an adjusting mechanism including a novel form of gearing affording a negative lost motion between the driving and driven parts thereof.

Another object is to provide an adjusting mechanism including a slip clutch connection between the driving and driven elements, and means whereby said slip clutch connection is initially rendered fully effective for driving a part through

a predetermined range at a relatively rapid rate and thereafter rendered effective to drive said part at a relatively much slower rate.

Various other objects and advantages of the invention will hereinafter appear.

The accompanying drawings illustrate several embodiments and adaptations of my invention which will now be described—it being understood that the invention is susceptible of embodiment in other forms without departing from the scope of the appended claims.

In the drawings,

Fig. 1 is a side elevational view (approximately one-half size) of a negative lost motion adjusting mechanism constructed in accordance with my invention, the same being adapted to control the rate of adjustment of a potentiometer or the like.

Fig. 2 is a top plan view of the device illustrated in Fig. 1.

Fig. 3 is an enlarged fragmentary sectional view, on the line 3—3 of Fig. 2, certain of the parts being shown in elevation.

Fig. 4 is an enlarged view of certain elements of the clutch mechanism.

Fig. 5 is a fragmentary view, in section on the line 5—5 of Fig. 3, showing the means for limiting the total range of driving or adjustment of the driven element in opposite directions respectively.

Fig. 6 is a fragmentary view, partly in section, showing a modification wherein my negative lost motion adjusting mechanism is adapted for adjustment or control of a butterfly valve or the like.

Fig. 7 illustrates schematically and diagrammatically a gas mixing control system having my negative lost motion adjustment mechanisms applied both to the control of a potentiometer and to a valve for controlling the proportionality of one of the constituents of a gaseous mixture, whereby the total heating value per unit volume of the latter is maintained substantially constant.

Fig. 8 is a schematic and diagrammatic illustration of a simplified form of gas mixing control system wherein my negative lost motion adjusting mechanism is associated with the proportioning valve.

Fig. 9 is a schematic and diagrammatic illustration of a system for the control of temperature in a heating oven or the like, wherein my negative lost motion adjusting mechanism is utilized to control the rate of supply of the combustible gaseous fuel.

Fig. 10 is a graphic illustration of a given

trend in variation of the total heating value per unit volume of a gaseous fluid or a mixture of gaseous fluids, or in the value of potential heat units supplied per unit of time, which value it is desired to maintain substantially constant.

Fig. 11 is a graphic illustration of the controlling effect upon the heating value per unit volume of a combustible fluid, in the event of a variation such as that illustrated in Fig. 10, as provided by a known form of adjusting and controlling mechanism.

Fig. 12 graphically illustrates a condition like that involved in Figs. 10 and 11, as controlled by a system embodying my aforementioned negative lost motion adjusting mechanism, and

Fig. 13 is a graphic illustration similar to Fig. 12—but showing the effect of a reduction in the degree of lost motion provided between certain parts of my negative lost motion adjusting mechanism.

Referring first to Figs. 1 to 5, inclusive, the numeral 15 (Figs. 2 and 3) designates a suitable relatively small, geared, reversible motor, which is adapted when in operation to drive a shaft 16 at a relatively slow speed; say, one revolution per minute. Motor 15 is preferably of the split-field reversible type, and any suitable means, such as those hereinafter described, may be employed to effect completion of the respective circuit connections thereof selectively, whereby the shaft 16 is rotated in one direction or the other or permitted to remain stationary. Shaft 16 is provided with a reduced end portion 16^a (Fig. 4) of circular form in transverse cross section which has a freely slidable or telescopic fit within a recess in the adjacent end of a shaft 17, as shown in dotted lines at 17^a in Fig. 4. Shaft 17 has keyed or otherwise non-rotatably attached to said end thereof a spur gear or pinion 18, which as shown herein is provided with eight teeth.

A driving connection between shafts 16 and 17 is provided by means of a pin 19 which preferably has a drive fit within an opening extending diametrically through the reduced portion 16^a of shaft 16, the arrangement being such that substantially equal lengths of said pin extend from opposite sides of shaft portion 16^a. The end of gear 18 adjacent to shaft 16 is preferably provided with a diametrically extending groove 18^a of approximately V-shape to normally accommodate the opposite ends of pin 19, as shown in Figs. 3 and 4, whereby shaft 16 may drive gear 18 and, consequently, the shaft 17. Shaft 17 is so mounted and spring-biased in the manner hereinafter described, as to provide for normal positioning thereof in the manner illustrated in full lines in Fig. 4. However, upon positive restraint of rotation of shaft 17 in one direction or the other, by the means hereinafter described, the ends of pin 19 are adapted to act upon one wall or the other of groove 18^a to force endwise against said bias the gear 18, shaft 17 and parts associated therewith, whereby shaft 16 may rotate independently of shaft 17.

As best illustrated in Figs. 2 and 3 motor 15 is attached, as by means of a plurality of bolts 20 and nuts 21 to the inner surface of the flat upper portion 22^a of bracket 22, which is provided at its lower portion with a pair of rearwardly extending arms 22^b and 22^c the ends 22^d and 22^e of which are bent outwardly at right angles thereto and perforated at a plurality of points, as indicated in dotted lines at 22^f and 22^g, Fig. 2, to accommodate the shanks of bolts or screws (not shown) whereby the bracket is attached to a wall, 75

panel or other suitable support. Said upper portion 22^a of the bracket is provided with an opening 22^h (Fig. 3) to accommodate the end bearing 15^a of the motor, from which shaft 16 projects.

5 The lower portion of bracket 22 is provided with an opening 22ⁱ (Fig. 3) having a conical countersink 22^j at its inner end. A shaft 23 (Fig. 3) has an integral flange or enlargement 23^a of octagonal or other polygonal contour, the inner 10 flat face of which is adapted to abut against the outer face of said lower portion of bracket 22; said shaft having an inner end portion 23^b which is adapted to fit snugly within opening 22ⁱ, and said end portion 23^b being upset or riveted against the peripheral wall of countersink 22^j, as shown at 23^c, to rigidly secure said shaft to said bracket. Shaft 23 has rotatably mounted thereon a relatively large gear 24, which meshes with gear 18, gear 24 preferably having one hundred and sixty teeth.

23 The bearing hub of gear 24 is designated by the numeral 24^a, said hub acting to space said gear from bracket 22 for normal full width engagement or meshing with pinion 18. Also rotatably supported upon shaft 23 is a gear 25, which preferably has one hundred and twenty-eight teeth, the bearing hub 25^a of which acts to properly space the same from gear 24. Meshing with gear 25 (normally at the left hand side of the teeth of the latter, Fig. 3) is a relatively narrower or thinner and smaller gear 26, which is preferably provided with forty teeth. Gear 26 is rotatably mounted upon the shaft 17, and the left-hand face or side thereof is frictionally engaged with a disk or plate 27 which is non-rotatably attached to shaft 17, as by means of a pin 28 which extends diametrically through the hub 27^a of said disk and through shaft 17 (see Figs. 3 and 4).

Pin 28 is preferably provided with an extension 28^a of enlarged diameter which cooperates with one or the other of a pair of blocks or lugs 29^a, 29^b carried by a metal bracket 29 which is rigidly attached to gear 24, in the manner illustrated in Figs. 3 and 5, as by means of a plurality of screws 29^c, 29^d and 29^e. When extension 28^a engages either of the blocks 29^a or 29^b, the shaft 17 is positively locked against further rotation in the direction in which it was being driven, with consequent stoppage of further rotation of gears 18, 26, 24 and 25 in a corresponding direction.

Upon such locking of said gears pin 19 (which is carried by the continuously rotatable motor shaft 16) acts to force shaft 17 endwise toward the right (Fig. 3) against its bias, thus permitting continued rotation of shaft 16 independently of shaft 17. During such endwise movement of shaft 17 pinion 18 and gear 26 are slid or displaced transversely relatively to the respective gears 24 and 25, without unmeshing said parts; thus insuring proper cooperation thereof upon reversal of the direction of rotation of motor 15.

As best illustrated in Fig. 3, a disk or plate 30 is rotatably mounted upon shaft 17, one flat face of said plate being adapted for engagement with the adjacent face of gear 26. The means for biasing shaft 17 toward the left (Fig. 3) and for holding plates 27 and 30 in frictional driving engagement with gear 26 preferably comprises a pair of coiled compression springs 31 and 32 which surround shaft 17. The right hand end of spring 31 in Fig. 3 abuts against the connecting portion 33^a of a substantially U-shaped bracket 33, the arms 33^b and 33^c of which have right angled perforated ends which are attached to the upper portion 22^a of bracket 22 as by means of a pair

of screws 34, 34 (Fig. 2). Portion 33^a of bracket 33 is perforated to accommodate and provide a bearing and support for one end of shaft 17, as shown in Fig. 3.

The other end of spring 31 abuts against the projecting ends of a pin 35, which preferably has a drive fit within an opening provided in shaft 17 at a predetermined point in its length. Spring 31 thus acts to bias shaft 17 and pinion 18 toward the left to the positions thereof shown in Fig. 3.

Spring 32 is interposed between pin 35 and the right hand face of plate 30 (Fig. 3), thus biasing plate 30 against one face of gear 26. This arrangement affords a slip-clutch driving connection between shaft 17 and gear 26. Springs 31 and 32 are preferably provided with sheet metal cups at the respective ends thereof, as shown.

In Figs. 1 to 5 I have shown my invention applied to the control or adjustment of a potentiometer type resistance varying device, which is designated in general by the numeral 36. The movable contact means of said potentiometer preferably comprises a punched and stamped member 37 composed of resilient sheet metal, such as phosphor bronze. The flat body portion of member 37 is rigidly attached to a flat insulating disk 38, as by means of two or more screws or rivets, one of which is shown at 39 in Fig. 3; disk 38 being in turn rigidly attached to gear 25, as by means of two or more screws 40.

Member 37 is provided with a pair of reflexed contact arms 37^a and 37^b, the tips of which are preferably arranged in alignment with and on opposite sides of the shaft 24. The tip of arm 37^b is located rather closely adjacent to but spaced from shaft 23 for engagement with a predetermined degree of pressure against the stationary contact ring 36^a carried by the insulating base 36^b of the potentiometer; said contact ring 36^a having a conducting plate 36^c electrically connected thereto, and said plate having a wiring terminal portion 36^d exposed at the periphery of base 36^b.

The tip of arm 37^a is spaced a substantially greater distance from shaft 23, whereby the same is adapted to engage at a variable point with the resistance wire coil 36^e (see Fig. 2) which is arranged in the form of an approximately complete circle and is carried by the insulating base 36^b. The two ends of coil 36^e are respectively electrically connected with a pair of wiring terminal members 36^f and 36^g, the three terminals jointly providing for electrical connection of the potentiometer in circuit in the usual manner.

The manner in which base 36 is non-rotatably attached to shaft 23 is best illustrated in Fig. 3. Thus said base is provided with a centrally located through passage 36^h which is adapted to freely accommodate a hollow ferrule 41 the exposed end portion of which is externally threaded, as shown at 41^a to accommodate a clamping nut 42. The inner end of ferrule 41 is provided with a flange 41^b which fits within a countersink or recess 36ⁱ in base 36, said nut acting to clamp the ferrule and base to each other. A metal washer 43 is preferably interposed between nut 42 and base 36.

Shaft 23 is provided with a portion 23^d of reduced cross section onto which ferrule 41 is adapted to slidably fit, the outer end 23^e of said shaft portion being threaded to accommodate a nut 44, whereby the ferrule 41 is clamped to shaft 23 as illustrated. A metal washer 45 is preferably interposed between nut 44 and the outer end of

ferrule 41. The arrangement is such that upon assembly of the parts as aforescribed the contact arms 37^a and 37^b will be bent or pressed toward plate 38 to a predetermined degree, thereby providing the desired degree of contact pressure of the respective tips thereof.

My device includes a stud or prong 46 which is rigidly attached to gear 25, as by means of a pair of screws 47, and projects radially therefrom to an extent sufficient to provide for positive engagement thereof with one or the other of the shank ends of a pair of screws or bolts 48 and 49, which are respectively adjustably carried by spaced lugs 29^f and 29^g formed integrally with and upstanding from the base portion of bracket 29, which is attached to gear 24 as aforescribed. As will be understood, screws 48 and 49 are adjustable (preferably to like degrees) as by means of a screwdriver, to provide for variation of the degree or range of lost motion between gears 25 and 24, for a purpose herein-after described.

It will be apparent from the foregoing description that my device is properly referred to as a negative lost motion mechanism. That is to say, in an ordinary lost motion mechanism a change in the direction of movement or rotation of the driving element will result in a delay in picking up or engaging the driven element for driving of the latter in the reverse direction; whereas with my arrangement upon a reversal of the direction of rotation of the driving element the driven element is not only immediately engaged for driving thereof in such reverse direction, but the rate of driving of the driven element is definitely increased or accelerated for a predetermined period of time. After the driven element is moved through a predetermined angle or distance at such accelerated rate, the lost motion between the elements of the gearing is taken up, whereupon the adjustable element (in this case the contactor member 37 of the potentiometer) is constrained to move at a predetermined relatively slow rate of speed, the slip-clutch connection between disks 27, 30 and gear 26 being utilized to permit such slow speed adjustment of the driven element.

In the modified form of the device illustrated in Fig. 6 the gears 24 and 25 may be identical with the corresponding gears aforescribed—it being understood that bracket 29 and its associated parts will be attached to gear 24 of Fig. 6 and that projection 46 will be attached to gear 25—such elements being omitted from Fig. 6 merely for the purpose of better illustrating the actual changes required. Thus in Fig. 6 I employ a relatively short shaft 50 (instead of shaft 23 aforescribed) upon which gears 24 and 25 are rotatably mounted, shaft 50 having portions 50^a, 50^b, 50^c (corresponding with portions 23^a, 23^b and 23^c of shaft 23) to provide for rigid and non-rotatable attachment thereof to bracket 22. The reduced and threaded end 50^d of said shaft is adapted to accommodate a nut 50^e and washer 50^f to retain gears 24 and 25 in assembled relation to the shaft while providing for relatively free rotation with respect thereto.

Gear 25 has rigidly and non-rotatably attached thereto, as by means of a plurality of screws 51^a, a member 51 which is formed to accommodate shaft end 50^d and its associated parts 50^e and 50^f, said member 51 having formed integrally therewith, and in concentric relation to shaft 50, a stub shaft 51^b, to which a hollow connecting ferrule 52 may be attached, as by

means of a set screw 52^a, said ferrule having associated therewith a second set screw 52^b for clamping engagement with a shaft 53, whereby the latter will rotate in one direction or the other in unison with stub shaft 51^b and gear 25. Shaft 53 may be directly attached to a valve, such as a butterfly valve, to provide for adjustment of the latter in the same manner as described in connection with the potentiometer aforementioned, such adjustment, as aforescribed, having the negative lost motion characteristic, among others.

Referring now to Fig. 7, wherein I have shown my negative lost motion adjusting mechanism applied to a gas mixing control system to improve the operative characteristics of the latter, the numeral 54 designates a branch conduit through which a combustible gas of relatively high total heating value per unit volume is adapted to flow in the direction indicated by the arrow, at a rate depending upon the adjustment of a butterfly valve or the like shown in dotted lines at 55. Numeral 56 designates a second branch conduit through which a lean gas of a known constant total heating value per unit volume, as, for instance, air, is adapted to flow at a constant volumetric rate per unit of time, from any suitable source. Branch conduits 54 and 56 communicate with a main conduit 57 in which the aforementioned rich and lean gases are mixed, and through which the resulting combustible gaseous mixture is adapted to flow to any suitable or desired point of use or storage.

In practice it is desirable to maintain as nearly constant as possible the total heating value per unit volume of the combustible mixture flowing in conduit 57. To this end, a continuous sample of the mixture is withdrawn from conduit 57 and supplied through piping 58 and 59 to a known form of calorimetric device, which is designated in general by the numeral 60. Means are also preferably provided to insure substantially atmospheric pressure of the sample supplied through piping 58, 59 to device 60, said means comprising an orifice plate or constriction 58^a in pipe 58, and a vent to atmosphere which preferably is in the form of a burner 61. The calorimetric device 60 is preferably of the relatively quick-acting precision type described and claimed in my Patent No. 2,238,606, dated April 15, 1941, to which reference may be had for a detailed description of the construction and mode of operation thereof. Here the various elements forming part of or associated with the calorimetric device 60 are designated by the same reference letters, or by the same reference numerals with a prime (') added, as in my aforementioned Patent No. 2,238,606.

More specifically S designates a resistor; S¹ a slide wire resistor having an automatically adjustable contactor 11'; HJ the hot junction elements; CJ the cold junction elements; 10' the indicating scale; G the galvanometer; RT a resistor subjected to the temperature of the tank liquid and responsive electrically to variations in said temperature; R¹ a resistor having a fixed or constant resistance value; 13' a dry battery to supply current for the potentiometer circuit; 14' an adjustable resistance or rheostat for manually establishing the desired value of current flow from battery 13' to compensate for depletion or weakening of the latter; 20' a milliammeter having connected in parallel therewith an adjustable resistance 21' and milliammeter 20' being utilized to assist in proper setting of the battery current by adjustment of rheostat 14'; 25' designates

in general the indicating and recording device associated with the calorimetric device 60, 72' being the indicator which cooperates with scale 10' as well as the recorder for cooperation with the movable chart. The elements of Fig. 7, as thus far described are adapted to operate automatically, in the manner disclosed in my aforementioned Patent No. 2,238,606, to effect indication and recordation of variations in the instantaneous total heating value per unit volume of the test gas.

However, in a gas mixing control system like that disclosed in Fig. 7 it is desired to effect automatic adjustment of the relative volumetric rates of flow of the rich and lean gases in such a manner as to compensate for variations in the total heating value per unit volume of the gaseous mixture. Accordingly the shaft 62 is rotatable in one direction or the other upon a departure of the needle of galvanometer G from its intermediate or null position, as an incident to an increase or a decrease in the total heating value per unit volume of the gaseous mixture. Shaft 62 has fixed thereto, as by means of a set screw or the like, a radially extending contactor 63, which is movable in one direction from an intermediate or neutral position to engage a stationary contact 64, or in the opposite direction to engage a stationary contact 65. Contactor 63 is preferably insulated from shaft 62 and has attached thereto a conductor 66 which leads to a stationary contact 67 forming part of a switch whose contactor 68 is normally biased to its closed position by spring means, as shown; said contactor being intermittently opened for a predetermined period as by means of a cam 69 which is continuously rotated by a motor 70. As shown, cam 69 is preferably so formed as to provide for alternate opening and closing of contactor 68 for substantially equal periods of time.

The system of Fig. 7 is preferably supplied with direct current from lines L¹, L² upon manual closure of a double-pole knife switch 11, 11'. Thus if it be assumed that the total heating value per unit volume of the mixture flowing in conduit 57 increases beyond a value preselected therefor, the calorimetric device 60 in response thereto will effect operation of galvanometer G in a direction to cause, through the medium of the mechanism 25', rotation of shaft 62, say in a clockwise direction, with consequent engagement of contactor 63 with contact 64. Then, if contactor 68 is engaged with contact 67, or upon closure of said contactor, a circuit will be completed for motor 72 to effect operation of the latter in a direction tending to effect movement of valve 55 toward its closed position.

If the valve 55 had last been moved toward its fully opened position, the operation of motor 72 just mentioned will act, through the negative lost motion adjusting mechanism enclosed within casting 72' to effect an initial relatively large degree, and relatively rapid rate of adjustment of valve 55 toward its closed position. If such adjustment of valve 55 is sufficient to reduce the total heating value per unit volume of the mixture in conduit 57 below the desired value thereof, the calorimetric device 60 will respond in such manner as to effect unbalancing of galvanometer G in an opposite sense or direction, with consequent rotation of shaft 62 in a clockwise direction to effect disengagement of contactor 63 from contact 64.

On the other hand, if such adjustment of valve 55 toward closed position is not sufficient to reduce the total heating value per unit volume of

the mixture below that preselected therefor, the contactor 63 will remain in engagement with contact 64, so that upon the next period of engagement of contactor 68 with contact 67 the motor 72 will again be energized for operation thereof in a direction tending to effect further movement of valve 55 toward closed position. Under these conditions, however, the lost motion between the gears of the negative lost motion adjusting mechanism will have been taken up, so that further adjustment of valve 55 toward closed position will be effected at a much slower rate than that initially provided therefor. The time period during which contactor 68 is disengaged from contact 67, by reason of the shape or form of cam 69, is preferably of such length as to permit the calorimetric device 60 to respond to a given adjustment of valve 55 before effecting another adjustment of the latter.

Similarly, if it be assumed that the total heating value per unit volume of the mixture in conduit 57 drops below that preselected therefor, the device 60 will respond to effect unbalancing of galvanometer G in an opposite direction from that aforescribed. As a consequence shaft 62 will be moved in a counterclockwise direction until contactor 63 is engaged with contact 65, whereupon, during the period of intermittent engagement of contactor 68 with contact 67, a circuit will be completed for motor 72 for effecting operation thereof in a direction tending to effect opening movement of valve 55. Due to the provision of my negative lost motion mechanism, as aforescribed, the initial adjustment of valve 55 toward its fully open position will be effected at a relatively rapid rate and to a relatively large degree, pending take-up of the aforementioned lost motion between gears 25 and 24. Subsequent adjustments of valve 55 toward open position, if necessary, will be made at a relatively slower rate, as controlled by the rate of movement of the large gear 24.

As will be apparent to those skilled in the art, the negative lost motion mechanism associated with valve 55 provides for a relatively more rapid rate of adjustment thereof temporarily following a change in the direction of adjustment of the control means, than would be possible with calorimetric devices of the prior art. The principal advantage of my control system embodying the negative lost motion mechanism, over a system lacking such mechanism, resides in the shortening of the hunting cycle. For example, in a given installation and under given conditions of variation in the total heating value per unit volume of the mixture the hunting cycle was found to be thirteen minutes; whereas in the same installation and under like conditions of variation, but with the negative lost motion mechanism omitted, the hunting cycle was found to be approximately twenty-three minutes. Although in the two instances just mentioned the heating value variations were approximately the same, the shorter hunting cycle resulting from the use of my negative lost motion mechanism represents a much closer control of the total heating value per unit volume of the mixture, with consequent insured maintenance of more nearly the desired total heating value per unit volume.

Although the calorimetric device 60 is of the relatively quick-acting precision type disclosed in my aforementioned Patent No. 2,238,606, it is desirable in certain installations to provide for even closer accuracy and continuous automatic checking of the device 60, as by means of a rela-

tively slower acting precision calorimeter 73 of the character disclosed in the Packard Patent No. 1,625,277, dated April 19, 1927. Such a combination of relatively quick-acting and relatively slow acting calorimetric devices is disclosed in Fig. 3 of my prior Patent No. 2,002,279, dated May 21, 1935.

The indicating and recording portion 14 of the relatively slow acting calorimetric device 73 includes a contactor 75 which is movable in one direction or the other from an intermediate or neutral position into engagement with one or the other of the stationary contacts 76 and 77, depending upon whether the total heating value per unit volume of the mixture in conduit 57, as determined by device 73, goes above or below the value preselected therefor. As shown, contactor 75 is connected by conductor 78 with a stationary contact 79, into and out of engagement with which a contactor 80 is moved intermittently through the medium of a cam 81, which is preferably like and driven simultaneously with the cam 69 aforescribed through the medium of the single motor 70 aforesaid. Calorimeter 73 is supplied with a sample of the mixture from conduit 57 through the medium of the aforementioned pipe 58 and a branch pipe 82, the orifice 58a and burner 61 likewise insuring substantially atmospheric pressure of the sample supplied to calorimeter 73.

An adjustable potentiometric type resistance varying device 83 has its contactor 84 connected with one terminal of galvanometer G, wherefore any change in the angular position of contactor 84 effects a corresponding change or correction in the calibration of the calorimetric device 60. The means for effecting adjustment of contactor 84 comprises a split-field reversible motor 85, like the motor 72 aforesaid. Moreover, the driving connection between motor 85 and the shaft 86 which carries contactor 84 includes my aforementioned lost motion mechanism, which is enclosed within a housing 87 (like the housing 12' associated with motor 72).

Thus, assuming a predetermined rise in the total heating value per unit volume of the gaseous mixture above the value preselected therefor, as determined by the calorimeter 73, contactor 75 will engage contact 76 to effect energization and operation of motor 85 in a direction to effect such adjustment of contactor 84 as will result in proper and precision calibration of the control circuits (as, for instance, of the operating coil of galvanometer G) of calorimeter 60. More particularly, the aforementioned negative lost motion mechanism will cause an initial relatively rapid rate and relatively large degree of adjustment of contactor 84, during the period of engagement of contactor 80 with contact 79, and pending take-up of the aforementioned lost motion between gear 25 and gear 24 (see Figs. 1 to 5). If contactor 75 remains in engagement with contact 76 upon the next period of engagement of contactor 80 with contact 79, a further adjustment of contactor 84 in the same direction, but at a much slower rate (and consequently of much smaller degree during the period of engagement of contactor 80 with contact 79) will be effected. Upon a predetermined fall in the total heating value of the gaseous mixture (either initially or as an incident of the hunting cycle) contactor 75 will be engaged with contact 77, so that during the first period of engagement of contactor 80 with contact 79 thereafter the motor 85 will be operated in the reverse direction

from that aforescribed, and the negative lost motion mechanism will act to effect a relatively rapid and relatively large degree of movement of contactor 64 in a corresponding direction. The adjustment of contactor 64 in reverse directions is repeated until no further adjustment thereof is necessary, whereupon the indicating and recording device 74 attains equilibrium, with consequent neutral positioning of its contactor 75, thus indicating that the calorimeter 60 has been properly calibrated automatically, and that the desired total heating value per unit volume of the gaseous mixture in conduit 57 has been attained.

In the simplified form of gas mixing control apparatus illustrated more or less diagrammatically in Fig. 8, all of the parts may be identical with corresponding parts in Fig. 7, which parts have been given like numerals of reference. Thus the rich gas is supplied through a branch conduit 54 having therein a butterfly valve 55 for controlling the volumetric rate of flow of gas therethrough. Air or other lean gas of predetermined constant total heating value per unit volume is supplied at a constant volumetric rate through branch conduit 56, said branch conduits opening to main conduit 57 wherein said gases are mixed and thence conveyed to a point of use or storage.

A continuous sample of the gaseous mixture is withdrawn from conduit 57 through piping 53 and 59 (constriction 58^a and burner 61 providing for substantially atmospheric pressure of such sample) and supplied to the calorimetric device 60, which as aforescribed is preferably of the quick-acting precision type disclosed in my aforementioned Patent No. 2,238,606. However, as will be understood by those skilled in the art, a relatively slower acting precision type calorimeter like that disclosed at 73 in Fig. 7 might be substituted for the calorimeter 60, if desired.

As shown, calorimeter 60 is provided with a contactor 63 which is movable automatically in one direction or the other from an intermediate or neutral position thereof into engagement with one or the other of the contacts 64 or 65, depending upon whether the total heating value per unit volume of the mixture rises or falls with respect to the value preselected therefor. Thus upon a predetermined rise in the total heating value per unit volume of the mixture it may be assumed that contactor 63 will engage contact 64, with consequent energization and operation of the split-field motor 72 in a manner tending to effect movement of valve 55 toward fully closed position. Due to the presence of my negative lost motion mechanism 72' as aforescribed a relatively large degree and a relatively rapid rate of movement of valve 55 toward closed position is effected, pending the taking up of the lost motion between gears 25 and 24 (Figs. 1 to 6). Thereafter the closing movement of valve 55 is continued (but at a relatively much slower rate) pending attainment of the desired total heating value per unit volume of the mixture with resultant balancing of the galvanometer circuit and consequent movement of contactor 63 to an intermediate or neutral position.

If desired, of course, an interrupter (like parts 67, 63, 69 and 70 of Fig. 7) may be provided in the conductor 66, to permit the effect of a given adjustment of valve 55 to be determined by calorimeter 60 prior to effecting a further adjustment of the valve.

The operation of the device of Fig. 8 in the event of a drop in the total heating value per unit

volume of the mixture below the value preselected therefor (either as a result of the aforementioned closing movement of valve 55 or as a result of a decrease in the total heating value of the gas in branch conduit 54) is believed to be apparent. Thus, under the conditions just mentioned the contactor 63 will be caused to engage contact 65, thereby effecting energization of motor 72 to cause operation thereof in the reverse direction. Such reverse operation of motor 72 will effect adjustment of valve 55 toward its fully open position, and due to the provision of said negative lost motion mechanism, said valve will be opened to a relatively large degree and at a relatively rapid rate, until the lost motion is again taken up between gear 25 and gear 24; whereupon further opening movement of the valve 55 will be effected at a relatively much slower rate, as determined by the rate of movement of gear 24.

In Fig. 9 I have shown my negative lost motion adjusting mechanism applied to the control of a butterfly valve or the like adapted to regulate the volumetric rate of supply of a combustible fluid to a heating oven or the like whereby the temperature within the latter is maintained substantially constant. Thus the numeral 88 designates a conduit through which a combustible gaseous fluid is adapted to flow under pressure from any suitable source. In practice the fluid flowing in conduit 88 will be subject to relatively wide variations in total heating value per unit volume thereof, wherefore variation in the volumetric rate of flow thereof to the burner 89 in oven 90 is necessary to provide for maintenance of a predetermined substantially constant temperature in the latter, assuming that a substantially constant number of heat units per unit of time are absorbed by the articles (not shown) to be treated in oven 90 or are dissipated from the oven by diffusion or otherwise.

On the other hand, even though the total heating value per unit volume of the fluid flowing in conduit 88 remains substantially constant, regulation of the rate of flow thereof by adjustment of valve 55 may be necessary due to variations in the rate of heat absorption from oven 90 (as by variation in the number of articles treated therein per unit of time, or by variation in the rate of heat dissipation from the oven by variations in ambient or external temperature, and variations in the frequency with which the oven is charged with articles to be heat treated). My system of oven temperature control functions equally well under all of the conditions aforementioned, or combinations of such conditions.

As will be noted, conduit 88 has its forward end 88^a reduced in diameter for positioning thereof within and in spaced relation to the surrounding wall of the enlarged tubular inlet end 89^a of burner 89. The combustible gas ejected from the reduced end or nozzle 88^a of conduit 88 thus acts as an injector to draw into the inlet end 89^a a proper volume of air for mixture with the combustible gas, which mixture is ignited and burned within oven 90, as indicated by the multiple jets or flames 91.

The temperature within oven 90 is preferably ascertained by one or more thermocouples, the thermocouple 92 illustrated acting in the usual or well known manner to effect generation of an electromotive force or electric current whose value is proportional to or corresponds with the value of the temperature within oven 90. Such electromotive force is utilized to control the oper-

ation of the contactor 93 of a so-called polarized relay 93, whose operating coil 93^b is electrically connected in a well known manner with the terminals of the thermocouple 92. As shown diagrammatically contactor 93^a is preferably biased, as by a spring 93^c or otherwise to one of its extreme positions wherein it engages the stationary contact 93^d of the relay.

It may be assumed that contactor 93^a engages contact 93^d when the temperature within oven 90 is below the value preselected therefor, and under these conditions a circuit will be completed intermittently, said circuit extending from line L² by conductor 94 through the contacts 95 of a switch (when closed intermittently through the medium of a cam 96 which is adapted for continuous rotation by a suitable motor 97), thence by conductor 98 through contactor 93^a and contact 93^d, conductor 99 through the closing winding 100 of an electromagnetically operable switch, whose normally open contacts are shown at 100^a, and thence by conductors 101, 102 and 103 to line L¹. Contacts 100^a when thus closed intermittently for a period depending upon the period of closure of contacts 95, are adapted to complete a circuit for the split field motor 72 for operation of the latter in one direction, which direction may be assumed to be such as to tend to effect opening movement of valve 55.

Due to the provision of my lost motion adjusting mechanism 72' (shown in detail in Figs. 1 to 6) a relatively rapid rate of opening movement of valve 55 is effected during initial closure of contacts 95, and during subsequent closure of said contacts, until the aforescribed lost motion between gear 25 and the gear 24 is taken up. If the contactor 93^a remains in engagement with contact 93^d the subsequent opening adjustments of valve 55 will be effected at a much slower rate (as determined by the rate of rotation of gear 24). When the desired temperature is eventually attained or exceeded within oven 90 contactor 93^a will be first disengaged from contact 93^d to discontinue operation of motor 72 in a direction to effect further opening of valve 55, and if the temperature within oven 90 exceeds the preselected value, contactor 93^a will be moved in an obvious manner into engagement with contact 93^e. Thereupon (during intermittent closure of contacts 95) a circuit will be completed in an obvious manner for the operating winding 104 of a second electromagnetically operable switch, the normally open contacts of which are shown at 104^a.

Contacts 104^a when closed intermittently are adapted to complete a reverse circuit for motor 72, whereby the latter tends to drive valve 55 toward its fully closed position. Upon such reversal of motor 72 said negative lost motion mechanism 72' acts to initially effect a relatively rapid rate and relatively large degree of closing movement of valve 55, during closure of contacts 95, and until the lost motion between gear 25 and gear 24 is taken up. Further closing movement of valve 55, if necessary, will be effected at a relatively much slower rate, as determined by the speed or rate of rotation of gear 24. Upon reduction of the temperature within oven 90 or below the value preselected therefor contactor 93^a will be permitted to disengage contact 93^e, and further adjustment of valve 55 will be discontinued pending re-engagement of said contactor with either of the aforementioned contacts 93^d or 93^e, as will be readily understood.

In Fig. 10 the curve at A illustrates the actual

total heating value per unit volume of a combustible gaseous mixture, which value may be assumed to be that desired or preselected for a given purpose, as indicated by the horizontal line B. The downwardly angled portion A¹ of curve A indicates the manner in which a given change in the total heating value per unit volume of the combustible mixture may take effect (assuming that there is no adjustment made in the volumetric proportionality of the rich and lean gaseous constituents of the mixture, and hence no control of the total heating value per unit volume of the mixture), the resultant new actual total heating value being eventually stabilized as indicated at A², which value is substantially lower than the desired or preselected value B. The dotted line C shows the manner in which the change in heating value would be indicated by a calorimetric device, the distance between the portion A¹ of curve A and line C indicating the time lag in response of such calorimetric device.

Fig. 11 graphically illustrates the manner in which the condition illustrated in Fig. 10 would be handled by the various systems illustrated herein, if my negative lost motion adjusting mechanism were omitted therefrom. Thus the short horizontal line B¹ may be considered to indicate coincidence of the actual and desired or preselected total heating value per unit volume of a combustible mixture, which corresponds with the aforementioned value A (and B) in Fig. 10. The portion D of the solid curved line indicates the actual change (decrease) in total heating value of the mixture. The substantially parallel downwardly angled line E formed of dashes to the right of portion D shows the actual indication of the total heating value by the calorimetric device, the spacing of said lines indicating the time lag of the calorimeter in responding to the change in heating value.

The point F illustrates diagrammatically the time at which the calorimeter responds to the change and attempts to adjust the valve or the like to increase the total heating value of the mixture. However, due to lost motion in the gearing, etc., no adjustment in the heating value is effected at points F, G and H, but when the point I in time is reached the lost motion will have been taken up, and a relatively slow and correspondingly small adjustment (opening) of the valve will be effected, to increase the actual heating value to that shown at J. Thereafter during corresponding time periods like small adjustments of the valve will be effected to increase the heating value of the mixture, as indicated at K, L and M.

During the next time period the valve will be further opened to increase the actual heating value of the mixture to that indicated at N, which, of course, is slightly above the value B¹ preselected therefor. At such time period however, as indicated in dotted lines at Q, the heating value indicated by the calorimeter is substantially below the value B¹, as an incident to the time lag in response of the calorimeter. Accordingly the valve is further opened to provide the actual heating values indicated at O and P. Prior to the next period for adjustment of the valve the indicated heating value will be at the point marked R in dotted lines and the calorimetric device will act to prevent any further opening adjustment of the valve.

The heating value indicated by the calorimeter will continue to rise until the point S is reached, whereupon the calorimeter will respond and at-

tempt to effect a closing adjustment of the valve, as indicated at T; but due to the aforementioned lost motion in the gearing, etc., no adjustment will be effected at any of the points T, U or V. When the point W, in time, is reached said lost motion will have been taken up and a closing adjustment of the valve will be effected, to reduce the total heating value of the mixture to that shown at X. Further closing adjustments are effected, as indicated by the values X^1 , X^2 , X^3 and X^4 ; whereas when the value X^4 is reached, and before the next adjustment period has arrived, the indicated total heating value will be as shown at point Y, so that the elements of the calorimeter will act to prevent further closing adjustment of the valve.

The actual total heating value X^4 will be maintained until the point Z is reached, whereupon the calorimeter will attempt to effect opening adjustments of the valve at each of the points Z^1 , Z^2 and Z^3 , but no adjustment can be made (due to the lost motion in the gearing) until point Z^4 is reached, whereupon the total heating value will be increased in sequence to the values Z^5 , Z^6 and Z^7 , the latter value being only slightly above the preselected value. As will be noted the degree of divergence of the actual total heating value from the preselected value becomes smaller and smaller after each series of opening and/or closing adjustments of the valve, until stabilization of the actual heating value at the preselected value is eventually effected. In like manner the variations indicated by the calorimeter are gradually decreased in magnitude, as shown by the dash-line curve E, etc.

The improvement in the control functions of the gas mixing control system or the like when my negative lost motion mechanism is employed is graphically illustrated in Fig. 12; wherein the portions B¹, D and E of the curves may be considered to indicate the same values as in Fig. 11. On the other hand when point F is reached (Fig. 12) the calorimeter is immediately effective to cause an opening adjustment of the valve; and, assuming a relatively large degree of separation of the abutment ends of the shanks of screws 48 and 49 (Fig. 1) to provide a relatively large degree of lost motion between gear 25 and gear 24, a correspondingly large degree of opening adjustment of the valve will be effected (as indicated at F¹ in Fig. 12) so that the actual heating value F² will be attained. Thereafter a series of relatively small opening adjustments of the valve will be effected (corresponding to those illustrated in Fig. 11) to sequentially provide for attainment of the heating values F², F³, F⁴, F⁵ and F⁶.

Due to the magnitude of the adjustment F¹, the calorimeter will earlier respond to the initial increase in heating value of the mixture, and also due to the earlier effective response of the calorimeter for making the initial adjustment, the lengths of the waves of the actual and indicated variations in the total heating value of the mixture will be much smaller than those illustrated in Fig. 11. Also due to said earlier effective response of the calorimeter initially, the magnitudes of the variations in the actual and indicated values of said total heating value will likewise be reduced by employment of my negative lost motion adjusting mechanism. The further graphic illustration in Fig. 12 of the operations and functions of the control mechanism with my improvement incorporated therein are

believed to be self-evident. As heretofore pointed out, I provide for a substantial reduction in the length of the hunting or stabilizing cycle, with a consequent closer and more accurate control of the total heating value of the mixture.

Fig. 13 graphically illustrates the manner in which the control system, including my negative lost motion adjusting mechanism responds to conditions like those illustrated in Fig. 12. In respect of Fig. 13, however, it is to be understood that the abutment ends of screws 48 and 49 (Fig. 1) will be adjusted or positioned relatively closely to each other to provide only a relatively small degree of lost motion between gear 25 and gear 24. Thus although the calorimeter will be effective immediately at point F (Fig. 13, the same as in Fig. 12) to cause an opening adjustment of the valve, nevertheless the degree of opening adjustment will be relatively small, as indicated by the line F⁷ showing the change in actual total heating value of the mixture. The following series of opening adjustments of the valve will be substantially equal to the initial adjustment, until the actual total heating value F⁸ is attained. Thereafter the control mechanism will function in the manner graphically illustrated in Fig. 13 to alternately effect series of closing and opening adjustments of the valve pending final attainment or stabilization of the total heating value of the mixture at the value preselected therefor. Although Figs. 12 and 13 respectively represent the effect of adjusting the screws 48 and 49 (Fig. 1) to provide substantially maximum and substantially minimum degrees of lost motion between gears 25 and 24, it is to be understood that various other degrees of adjustment of either or both of the screws 48 and 49 may be effected, as may be desired to meet the particular characteristics of the calorimetric device (in respect of time lag in response, etc.), or other conditions of a particular installation.

What I claim as new and desire to secure by Letters Patent is:

1. In a gas mixing control system, in combination, a pair of branch conduits through which a rich gas of variable total heating value per unit volume and a lean gas of constant total heating value per unit volume are respectively adapted to flow, a main conduit into which said branch conduits discharge to provide for mixture of said gases, an adjustable valve in one of said branch conduits, means for automatically adjusting said valve to vary the volumetric proportionality of said gases whereby the total heating value per unit volume of the mixture is maintained substantially constant, said last mentioned means comprising a calorimetric device adapted to continuously burn a volumetrically constant sample of said mixture to ascertain the total heating value per unit volume thereof, a reversible electric motor subject to control by said calorimetric device, gearing interposed between said motor and said valve to provide for opening or closing movement of the latter in accordance with the direction of operation of said motor, and means associated with said gearing to compensate for inherent lost motion in the latter as an incident to each reversal of the direction of rotation of said motor, said last mentioned means providing for initial opening or closing movement of said valve at a rate faster than normal upon each reversal of the direction of rotation of said motor.

2. In a gas mixing control system, in com-

bination, a pair of branch conduits through which a rich gas of variable total heating value per unit volume and a lean gas of constant total heating value per unit volume are respectively adapted to flow, a main conduit into which said branch conduits discharge to provide for mixture of said gases, an adjustable valve in one of said branch conduits, means for automatically adjusting said valve to vary the volumetric proportionality of said gases whereby the total heating value per unit volume of the mixture is maintained substantially constant, said last mentioned means comprising a calorimetric device adapted to continuously burn a volumetrically constant sample of said mixture to ascertain the total heating value per unit volume thereof, a reversible electric motor subject to control by said calorimetric device, gearing interposed between said motor and said valve to provide for opening or closing movement of the latter in accordance with the direction of operation of said motor, and means associated with said gearing to compensate for inherent lost motion in the latter as an incident to each reversal of the direction of rotation of said motor, said last mentioned means including a slip clutch driving connection between said motor and certain of the gears of said gearing, to thereby provide for initial opening or closing movement of said valve at a rate faster than normal upon each reversal of the direction of rotation of said motor.

3. In a gas mixing control system, in combination, a pair of branch conduits through which a rich gas of variable total heating value per unit volume and a lean gas of constant total heating value per unit volume are respectively adapted to flow, a main conduit into which said branch conduits discharge to provide for mixture of said gases, an adjustable valve in one of said branch conduits, means for automatically adjusting said valve to vary the volumetric proportionality of said gases whereby the total heating value per unit volume of the mixture is maintained substantially constant, said last mentioned means comprising a calorimetric device adapted to continuously burn a volumetrically constant sample of said mixture to ascertain the total heating value per unit volume thereof, a reversible electric motor subject to control by said calorimetric device, gearing interposed between said motor and said valve to provide for opening or closing movement of the latter in accordance with the direction of operation of said motor, means associated with said gearing to compensate for inherent lost motion in the latter as an incident to each reversal of the direction of rotation of said motor, said last mentioned means including a slip clutch driving connection between said motor and certain of the gears of said gearing, and said last mentioned means also including a manually adjustable lost motion driving connection between certain of the gears of said gearing, to thereby provide for initial opening or closing movement of said valve at a rate faster than normal upon each reversal of the direction of rotation of said motor.

4. In a gas mixing control system, in combination, a pair of branch conduits through which a rich gas of variable total heating value per unit volume and a lean gas of constant total heating value per unit volume are respectively adapted to flow, a main conduit into which said branch conduits discharge to provide for mixture of said gases, an adjustable valve in one of said branch conduits, means for automatically adjusting said

valve to vary the volumetric proportionality of said gases whereby the total heating value per unit volume of the mixture is maintained substantially constant, said last mentioned means comprising a calorimetric device adapted to continuously burn a volumetrically constant sample of said mixture to ascertain the total heating value per unit volume thereof, a reversible electric motor subject to control by said calorimetric device, gearing interposed between said motor and said valve to provide for opening or closing movement of the latter in accordance with the direction of operation of said motor, means associated with said gearing to compensate for inherent lost motion in the latter as an incident to each reversal of the direction of rotation of said motor, said last mentioned means including a slip clutch driving connection between said motor and certain of the gears of said gearing, said last mentioned means also including a manually adjustable lost motion driving connection between certain of the gears of said gearing, and said lost motion driving connection between said last mentioned gears providing for initial opening or closing movement of said valve at a rate faster than normal upon each reversal of the direction of rotation of said motor.

5. In a gas mixing control system, in combination, a pair of branch conduits through which a rich gas of variable total heating value per unit volume and a lean gas of constant total heating value per unit volume are respectively adapted to flow, a main conduit into which said branch conduits discharge to provide for mixture of said gases, an adjustable valve in one of said branch conduits, means for automatically adjusting said valve to vary the volumetric proportionality of said gases whereby the total heating value per unit volume of the mixture is maintained substantially constant, said last mentioned means comprising a calorimetric device adapted to continuously burn a volumetrically constant sample of said mixture to ascertain the total heating value per unit volume thereof, a reversible electric motor subject to control by said calorimetric device, gearing interposed between said motor and said valve to provide for opening or closing movement of the latter in accordance with the direction of operation of said motor, means associated with said gearing to compensate for inherent lost motion in the latter as an incident to each reversal of the direction of rotation of said motor, said last mentioned means including a slip clutch driving connection between said motor and certain of the gears of said gearing, said last mentioned means also including a manually adjustable lost motion driving connection between certain of the gears of said gearing, said lost motion driving connection between said last mentioned gears providing for initial opening or closing movement of said valve at a rate faster than normal upon each reversal of the direction of rotation of said motor, said calorimetric device being of the relatively quick-acting precision type, a relatively slower acting precision type calorimetric device also adapted to continuously burn a volumetrically constant sample of said mixture to ascertain the total heating value per unit volume of the latter, a second reversible electric motor subject to control by said last mentioned calorimetric device for operation of the former in one direction or the other in response to an increase or decrease in the indicated total heating value per unit volume of said mixture with respect to a value preselected

therefor, a potentiometer type rheostat included in circuit with said calorimetric device first mentioned to provide for calibration of the latter, and means including gearing providing a negative lost motion driving connection between said second motor and a movable element of said potentiometer rheostat, said negative lost motion driving connection initially providing for substantially instantaneous operation of said movable element upon each reversal of operation of said second motor, to thereby compensate for the inherent lost motion in said gearing.

6. In a gas mixing control system, in combination, a pair of branch conduits through which a rich gas of variable total heating value per unit volume and a lean gas of constant total heating value per unit volume are respectively adapted to flow, a main conduit into which said branch conduits discharge to provide for mixture of said gases, an adjustable valve in one of said branch conduits, means for automatically adjusting said valve to vary the volumetric proportionality of said gases whereby the total heating value per unit volume of the mixture is maintained substantially constant, said last mentioned means comprising a calorimetric device adapted to continuously burn a volumetrically constant sample of said mixture to ascertain the total heating value per unit volume thereof, a reversible electric motor subject to control by said calorimetric device, gearing interposed between said motor and said valve to provide for opening or closing movement of the latter in accordance with the direction of operation of said motor, means associated with said gearing to compensate for inherent lost motion in the latter as an incident to each reversal of the direction of rotation of said motor, said last mentioned means including a slip clutch driving connection between said motor and certain of the gears of said gearing, said last mentioned means also including a manually adjustable lost motion driving connection between certain of the gears of said gearing, said lost motion driving connection between said last mentioned gears providing for initial opening or closing movement of said valve at a rate faster than normal upon each reversal of the direction of rotation of said motor, said calorimetric device being of the relatively quick-acting precision type, a relatively slower acting precision type calorimetric device also adapted to continuously burn a volumetrically constant sample of said mixture to ascertain the total heating value per unit volume of the latter, a second reversible electric motor subject to control by said last mentioned calorimetric device for operation of the former in one direction or the other in response to an increase or decrease in the indicated total heating value per unit volume of said mixture with respect to a value preselected therefor, a potentiometer type rheostat included in circuit with said calorimetric device first mentioned to provide for calibration of the latter, and means including gearing and a slip clutch providing a negative lost motion driving connection between said second motor and a movable element of said potentiometer rheostat, certain of the gears of said gearing having an adjustable lost motion connection therebetween whereby said slip clutch is rendered effective to cause a relatively rapid and relatively large initial adjustment of said movable element upon each reversal of operation of said second motor pending take-up of the lost motion between said gear, and said gears being

adapted to thereafter reduce the rate of adjustment of said element.

7. In a gas mixing control system, in combination, a pair of branch conduits through which a rich gas of variable total heating value per unit volume and a lean gas of constant total heating value per unit volume are respectively adapted to flow, a main conduit into which said branch conduits discharge to provide for mixture of said gases, an adjustable valve in one of said branch conduits, means for automatically adjusting said valve to vary the volumetric proportionality of said gases whereby the total heating value per unit volume of the mixture is maintained substantially constant, said last mentioned means comprising a calorimetric device adapted to continuously burn a volumetrically constant sample of said mixture to ascertain the total heating value per unit volume thereof, a reversible electric motor subject to control by said calorimetric device, gearing interposed between said motor and said valve to provide for opening or closing movement of the latter in accordance with the direction of operation of said motor, means associated with said gearing to compensate for inherent lost motion in the latter as an incident to each reversal of the direction of rotation of said motor, said last mentioned means including a slip clutch driving connection between said motor and certain of the gears of said gearing, said last mentioned means also including a manually adjustable lost motion driving connection between certain of the gears of said gearing, said lost motion driving connection between said last mentioned gears providing for initial opening or closing movement of said valve at a rate faster than normal upon each reversal of the direction of rotation of said motor, said calorimetric device being of the relatively quick-acting precision type, a relatively slower acting precision type calorimetric device also adapted to continuously burn a volumetrically constant sample of said mixture to ascertain the total heating value per unit volume of the latter, a second reversible electric motor subject to control by said last mentioned calorimetric device for operation of the former in one direction or the other in response to an increase or decrease in the indicated total heating value per unit volume of said mixture with respect to a value preselected therefor, a potentiometer type rheostat included in circuit with said calorimetric device first mentioned to provide for calibration of the latter, and means including gearing and a slip clutch providing a negative lost motion driving connection between said second motor and a movable element of said potentiometer rheostat, certain of the gears of said gearing having an adjustable lost motion connection therebetween whereby said slip clutch is rendered effective to cause a relatively rapid and relatively large initial adjustment of said movable element upon each reversal of operation of said second motor pending take-up of the lost motion between said gears, said gears being adapted to thereafter reduce the rate of adjustment of said element, and associated means adapted to intermittently interrupt operation of either or both of said motors under all conditions tending to effect operation thereof, for the purpose set forth.

8. In a control system, in combination, means responsive to variations in a condition such as temperature, means subject to control by said first mentioned means for increasing or decreasing the supply of a medium whereby the value

of said condition is maintained substantially constant, and the aforementioned means including a negative lost motion adjustment mechanism operable automatically to effect an initial increase or decrease in the rate of supply of said medium which is relatively more rapid and larger than normal, upon each decrease or increase respectively in the value of said condition with respect to a value preselected therefor.

9. In a gas mixing control system, in combination, means including a calorimetric device continuously responsive to variations in the total heating value per unit volume of a flowing mixture of combustible gases, with respect to a value preselected therefor, means including a valve subject to control by said calorimetric device for varying the volumetric proportionality of said combustible gases whereby said value is maintained substantially constant, said valve having associated therewith a negative lost motion adjustment mechanism whereby the former is initially subjected to a relatively rapid rate and relatively large degree of adjustment in one direction or the other upon each departure of said mixture from the total heating value per unit volume preselected therefor, and said last mentioned mechanism also providing for subsequent intermittent adjustment of said valve in a like direction at a relatively slower rate pending departure of said mixture in an opposite sense from said total heating value per unit volume preselected therefor.

10. In a gas mixing control system, in combination, a pair of branch conduits through which a rich gas of variable total heating value per unit volume and a lean gas of constant total heating value per unit volume are respectively adapted to flow, an adjustable valve in one of said branch conduits, a main conduit into which said branch conduits discharge to provide for mixture of said gases, a calorimeter adapted to withdraw and burn a continuous volumetrically constant sample of said mixture to provide for ascertainment of the total heating value per unit volume thereof with respect to a value preselected therefor, a reversible electric motor subject to control by said calorimeter, and means comprising a negative lost motion driving connection between said motor and said valve, said negative lost motion driving connection serving to minimize the hunting period of adjustment of said valve as an incident to each increase or decrease in the total heating value per unit volume of said mixture resulting from an increase or decrease in the total heating value per unit volume of said rich gas.

11. In a control system, in combination, means responsive to variations in a condition such as temperature, means subject to control by said first mentioned means for increasing or decreas-

ing the supply of a medium whereby the value of said condition is maintained substantially constant, the aforementioned means including means operable automatically to effect a relatively rapid and relatively large initial increase or decrease in the rate of supply of said medium upon each decrease or increase respectively in the value of said condition with respect to a value preselected therefor, said last mentioned means being also thereafter operable automatically to effect intermittent relatively smaller normal increases or decreases in said rate of supply pending attainment of a given value of said condition, for the purpose set forth.

15 12. In a control system of the character described, in combination, a conduit through which a combustible gas of variable total heating value per unit volume is adapted to flow, an adjustable valve in said conduit, means for continuously ascertaining the heating effect of combustion of said flow of gas, means responsive to variations in said heating effect for automatically adjusting said valve to vary the volumetric rate of flow of said gas whereby said heating effect is maintained substantially constant, said last mentioned means including a reversible electric motor, gearing interposed between said motor and said valve to provide for opening or closing movement of the latter in accordance with the direction of operation of said motor, and means including a friction slip clutch associated with said gearing to compensate for inherent lost motion in the latter as an incident to each reversal of the direction of rotation of said motor, said last mentioned means being effective to provide for initial opening or closing movement of said valve at a rate faster than normal, for the purpose set forth.

30 13. In a control system of the character described, in combination, means responsive to variations in a condition such as temperature, means including an adjustable valve subject to control by said first mentioned means for increasing or decreasing the rate of supply of a medium whereby said condition is maintained at a predetermined substantially constant value, the aforementioned means including motor means operable automatically to effect a relatively rapid and relatively large initial adjustment of said valve to effect a corresponding relatively large initial increase or decrease in the rate of supply of said medium upon each decrease or increase respectively in the value of said condition with respect to the aforementioned value predetermined therefor, and the aforementioned means also acting to thereafter insure relatively slower and relatively smaller adjustments of said valve, for the purpose set forth.
